US00D750660S

(12) United States Design Patent
Caldwell

(10) Patent No.: US D750,660 S
(45) Date of Patent: * Mar. 1, 2016

(54) DISPLAY SCREEN OR PORTION THEREOF
WITH A GRAPHICAL USER INTERFACE

(71) Applicant: MX Technologies, Inc., Lehi, UT (US)

(72) Inventor: John Ryan Caldwell, Lehi, UT (US)

(73) Assignee: MX Technologies, Inc., Lehi, UT (US)

() Term: 15 Years

(21) Appl. No.: 29/542,985

(22) Filed: Oct. 20, 2015

Related U.S. Application Data

(63) Continuation of application No. 13/507,601, filed on Jul. 12, 2012.

(51) LOC (10) Cl. 14-04

(52) U.S. Cl.

USPC D14/486

CLAIM

The ornamental design for a display screen or portion thereof with a graphical user interface, as shown and described.

DESCRIPTION

The FIGURE is a front view of a display screen or portion thereof with a graphical user interface in accordance with my design.

The broken lines shown in the drawing illustrate a mobile device and portions of the display screen or portion thereof with a graphical user interface that forms no part of the claimed design.
